UNITED STATES PATENT OFFICE.

ROBERT M. KEATING, OF SPRINGFIELD, MASSACHUSETTS; BRIGHTIE E. BRUTNELL, EXECUTRIX OF SAID ROBERT M. KEATING, DECEASED, ASSIGNOR, BY MESNE ASSIGNMENTS, TO KEATING VALVE COMPANY, INCORPORATED, OF SPRINGFIELD, MASSACHUSETTS.

FLUSHING VALVE.

Application filed May 6, 1920. Serial No. 379,376.

To all whom it may concern:

Be it known that I, ROBERT M. KEATING, citizen of the United States, residing at Springfield, in the county of Hampden and 5 State of Massachusetts, have invented a new and useful Improvement in Flushing Valves, of which the following is a specification.

This invention relates to the construction of automatic self-closing water-closet flushing valves of the type illustrated and described in U. S. Letters Patent No. 1,220,856, March 27, 1917, and No. 1,242,200, October 9, 1917, in which there is a main valve controlling the supply of flushing water and 10 connected with a piston that retards the closing of the main valve, a spring closed starting valve connected with the operating handle, that on being opened admits water to the retarding chamber and opens the main valve 15 and then closes the passage to the retarding chamber and draws the main valve closed, and an adjustable controlling valve for determining the speed of closing movement of the piston and main valve and consequently 20 governing the amount of water that flows for the main flush and the after flush which is permitted for filling the flushed bowl.

The object of the present invention is to provide a construction for such valves which 25 simplifies and cheapens their manufacture and renders them more efficient, durable and reliable.

In the accompanying drawings Fig. 1 shows a side elevation of a flushing valve that embodies the invention. Fig. 2 shows a 30 central section of the valve with the parts in closed position. Fig. 3 is a similar view with the parts in the positions occupied when the handle is depressed and the valves are opened 35 for starting a flushing flow to a bowl. Fig. 4 shows the same with the starting valve closed and the main valve open but commencing its closing movement as when a 40 bowl is being flushed.

The casing of the valve illustrated is made 45 in two cylindrical sections, a body section 1 and a cap section 2 that is screwed into the body section. The body section at its lower end has a threaded opening 3 for the connection of the intake pipe and on its side has a

threaded hub 4 for the connection of the discharge pipe. In the interior of the body section between the intake and discharge openings is an integral flange 6 containing a groove in which a packing 7 is located. The 55 cap section has a central depending sleeve 8, the lower end of which is reduced in diameter and provided with a packing gland 9 and a nut 10. Set in the closed top of the cap section at one side of the center is a 60 socket 11 which is internally threaded and near its lower end is provided with radial ports 12.

The main valve seat 13 is located in the lower face of the seat cage 14 that is screwed 65 into the upper end of the volume regulator cage 15. The head of the regulator cage rests upon the packing in the grooved flange in the interior of the casing and the upper end of the seat cage fits into the lower end of the cap section so that when the cap section is screwed down into the body section the seat cage is held in place and the regulator cage is forced down upon the packing in the flange. Rotatably fitted on the lower ported 70 section of the regulator cage that depends into the water way opposite the intake opening is a cylindrical ported shutter 16. By turning the shutter and adjusting its ports with relation to the ports in the regulator 75 cage the area of the openings from the water way into the regulator cage may be fixed to the degree made necessary by the pressure of the water in the system in which the valve is used. When the cap section is unscrewed 80 from the body section the seat cage with the seat and the regulator cage with the shutter are free to be lifted out.

The main valve 18 is movable up and down in the regulator cage, being guided by 85 the walls thereof and located therein before the seat cage and regulator cage are screwed together. The upper end of the main valve is beveled and closes upwardly with the water pressure against the valve seat 13. A 90 ported hub 19 extends down from the bottom of the main valve. The main valve is screwed upon the lower end of a tubular stem 95 20 which extends upwardly about the sleeve 8 that depends from the cap, a slight space 100

being left between the inner wall of the stem and the outer wall of the sleeve for the passage of water to the retarding chamber 17. The upper end of the main valve stem is 5 secured to a piston 21 that fits and is movable up and down in the cap section of the casing above the top of the seat cage. The piston has a packing 22 which is held in place by a plate 23 secured to the upper side of the piston. A tube 24 that opens through the piston is fastened at one side of the center so as to extend downward from the piston. The lower end of this tube is closed and above the bottom the side wall of the tube is provided with a thin longitudinally extending slit 25.

The starting valve seat 26 is located in the lower end of the main valve stem and is retained in place when the main valve is 20 screwed upon the valve stem. The starting valve 27 is a cylindrical block of metal with a conical upper face and it fits within and is guided in its movements up and down by the walls of the ported hub 19 that extends 25 down from the under side of the main valve. The starting valve is screwed upon the lower end of a spindle 28 and is secured in proper adjustment by a lock nut 29 before the main valve is screwed upon its stem. The starting 30 valve spindle extends upward through the starting valve seat, main valve stem, packing gland, and into the sleeve that depends from the cap where it is attached to a plunger 30 which is provided above the 35 cap with an operating handle 31. Surrounding the starting valve spindle in the sleeve is a spring 32 arranged to thrust between the lower end of the sleeve and the bottom of the plunger for normally holding 40 the starting valve tightly against its seat and through the starting valve holding the main valve against its seat.

A tube 33 extends loosely through the socket 11 in the cap and down into the slotted tube 24 that projects downward from the piston. Near its upper end the tube 33 has a flange 34 which rests upon the bottom of the socket for supporting the tube, and below the flange is a squared portion 35 that fits the similarly shaped hole in the bottom of the socket to prevent the tube from rotating. The upper edge of the tube is provided with notches 36, and turning into the upper end is a screw 37 with a needle point that, depending upon the distance the screw is turned in, regulates the area of the opening into the upper end of the tube. The sides of the screw are provided with longitudinal grooves 38. A plug 39 is screwed 60 into the socket over the end of the tube and control valve screw.

In assembling the structure the piston is first placed in the cap section with the cap tube extending into the piston tube. The 65 handle with the lifting spring and start-

ing valve spindle is then thrust through the cap sleeve, gland and main valve stem and the starting valve locked on the spindle in such position that the spring will hold it closed. The main valve seat 70 cage is then inserted into the cap, after which the main valve is screwed upon its stem until it rests against the under side of the starting valve seat. The regulator cage is then screwed upon the seat cage and after 75 the shutter has been adjusted so as to regulate the area of the intake ports the body portion is placed over these parts and screwed onto the cap portion.

To operate the valve the handle is pushed 80 down against the thrust of the spring. This first opens the starting valve and lets water under pressure on the intake side of the main valve up through the valve stem into the retarding chamber above the piston. 85 Continued downward movement of the handle causes the lower side of the starting valve to engage the bottom of the hub projecting from the main valve and draw the main valve down away from its seat. Water 90 from the intake passing through the regulator ports then flows through the main valve seat and seat cage to the discharge opening. When pressure is removed from the handle the spring at once draws the 95 starting valve tightly against its seat. This closes the passage up through the main valve stem to the retarding chamber. The upward thrust of the spring through the starting valve and starting valve seat then causes the 100 main valve to rise, but the main valve rises only as fast as the piston moves up and the piston can rise only as rapidly as it drives the water out of the retarding chamber through the ports in the socket in the cap, 105 through the notches in the upper end of the cap tube, down through the grooves in the control screw and through the cap tube into the piston tube, from which the water can only escape through the thin slit in its side. 110 When the piston is way down this slit is fully open. As the piston rises the cap tube gradually closes the slit in the piston tube, so that while the control screw governs the speed at which the water can escape from the 115 retarding chamber the speed is gradually checked as the piston nears the upper end of the chamber, by the restriction of the area of the slit through which the retarding water escapes. This provides for the required after flush and causes the main valve to close without water hammer.

The invention claimed is:

1. A flushing valve comprising a casing provided with intake and discharge openings and an internal flange, a regulator cage supported by said flange in the lower part of the casing, a seat cage secured to the regulator cage, a main valve seat held between said cages, a main valve movable in and 125

guided by the walls of said regulator cage toward and from the main valve seat, a tubular main valve stem screwed into the main valve, a starting valve seat secured in the 5 main valve by the tubular main valve stem, a ported hub depending from the main valve, a starting valve movable in and guided by the walls of said ported hub toward and from the starting valve seat, a piston connected with said tubular main valve stem and movable in the upper part of the casing, a handle 10 connected with the starting valve, a spring for lifting the handle, and a valve controlling a passage from above to below the piston.

2. A flushing valve comprising a casing, a main valve seat, a main valve movable toward and from the main valve seat, a starting valve seat carried by the main valve, a starting valve movable toward and from the starting valve seat, a handle connected with the starting valve, a spring for lifting the handle, a piston connected with the main valve, a ported tube carried by and extending 25 downward from the piston, a tube supported by the top of the casing and extending downward through the piston and into the piston tube, and a valve screw turning in the upper end of the tube supported from the casing.

3. A flushing valve comprising a casing, a main valve seat, a main valve movable toward and from the main valve seat, a starting valve seat carried by the main valve, a starting valve movable toward and from the starting valve seat, a handle connected with the starting valve, a spring for lifting the handle, a piston connected with the main valve, a tube with a thin longitudinally extending slit carried by and extending downward from the piston, a tube supported by the top of the casing and extending downward through the piston and into the piston tube, and a valve screw turning in the upper 40 end of the tube supported from the casing.

4. A flushing valve comprising a casing, a main valve seat, a main valve movable toward and from the main valve seat, a starting valve seat carried by the main valve, a starting valve movable toward and from the starting valve seat, a handle connected with the starting valve, a spring for lifting the handle, a piston connected with the main valve, a ported tube carried by and extending 55 downward from the piston, a socket set in the top of the casing, a tube loosely supported by said socket and extending downward through the piston and into the piston tube, and a valve screw turning in the upper end of the tube supported from the casing.

5. A flushing valve comprising a casing, a main valve seat, a main valve movable toward and from the main valve seat, a starting valve seat carried by the main valve, a

starting valve movable toward and from the starting valve seat, a handle connected with the starting valve, a spring for lifting the handle, a piston connected with the main valve, a slotted tube carried by and extending downward from the piston, a tube supported by the top of the casing and extending downward through the piston into the piston tube past the slot therein when the main valve is closed, and a valve screw turning in the upper end of the tube supported from the casing.

6. A flushing valve comprising a casing, a main valve seat, a main valve movable toward and from the main valve seat, a starting valve seat carried by the main valve, a starting valve movable toward and from the starting valve seat, a handle connected with the starting valve, a spring for lifting the handle, a piston connected with the main valve, a ported tube carried by and extending downward from the piston, a tube supported by the top of the casing and extending downward through the piston and into the piston tube, and a valve screw with longitudinal grooves in its side turning in the upper end of the tube supported from the casing.

7. A flushing valve comprising a casing, a main valve seat, a main valve movable toward and from the main valve seat, a starting valve seat carried by the main valve, a starting valve movable toward and from the starting valve seat, a handle connected with the starting valve, a spring for lifting the handle, a piston connected with the main valve, a ported tube carried by and extending downward from the piston, a removable socket set in the top of the casing, a tube with a flange resting on the bottom of said socket and extending downward through the piston and into the piston tube, and a valve screw turning in the upper end of the tube supported from the casing.

8. A flushing valve comprising a casing, a main valve seat, a main valve movable toward and from the main valve seat, a starting valve seat carried by the main valve, a starting valve movable toward and from the starting valve seat, a handle connected with the starting valve, a spring for lifting the handle, a piston connected with the main valve, a ported tube carried by and extending downward from the piston, a removable ported socket set in the top of the casing, a tube loosely supported by said socket and having a squared portion extending downward through a similarly shaped hole in the socket and into the piston tube, and a valve screw turning in the upper end of the tube supported from the casing.

9. A flushing valve comprising a casing, a main valve seat, a main valve movable toward and from the main valve seat, a starting valve seat carried by the main valve, a

starting valve movable toward and from the starting valve seat, a handle connected with the starting valve, a spring for lifting the handle, a piston connected with the main valve, a slotted tube carried by and extending downward from the piston, a tube supported by the top of the casing and extend-

ing downward through the piston into the piston tube past the slot therein when the main valve is closed, a removable plug holding the casing tube in position, and a valve screw turning in the upper end of the tube supported from the casing.

ROBERT M. KEATING.
